(57) **CLAIM**

The ornamental design for a fixture as shown and described.

DESCRIPTION

FIG. 1 is a front, right-side and top perspective view of a fixture showing our new design;

FIG. 2 is another front, right-side and top perspective view thereof;

FIG. 3 is a front, left-side and bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a perspective view of the fixture of FIG. 1 shown in a position of use with environmental subject matter.

The broken lines depict portions of the fixture that form no part of the claimed design.

The additional broken lines in FIG. 10 depict environmental subject matter that forms no part of the claimed design.
